CLAIM

We claim the ornamental design for a laptop having a foldable and detachable solar array, as shown and described.

DESCRIPTION

FIG. 1 is a front perspective view of a laptop having a foldable and detachable solar array, showing our new design in a closed position;

FIG. 2 is a rear perspective view of FIG. 1;

FIG. 3 is a front elevational view of FIG. 1;

FIG. 4 is a rear elevational view of FIG. 1;

FIG. 5 is a left-side elevational view of FIG. 1;

FIG. 6 is a right-side elevational view of FIG. 1;

FIG. 7 is a top plan view of FIG. 1;

FIG. 8 is a bottom plan view of FIG. 1;

FIG. 9 is a front perspective view thereof, illustrated in an open position;

FIG. 10 is a rear perspective view of FIG. 9;

FIG. 11 is a rear elevational view of FIG. 9;

FIG. 12 is a right-side elevational view of FIG. 9;

FIG. 13 is a left-side elevational view of FIG. 9;

FIG. 14 is a bottom perspective view of FIG. 9; and,

FIG. 15 is a perspective view thereof, illustrated with the solar array detached from the laptop computer.

The broken lines in FIG. 15 representing a power cord depict environmental matter and form no part of the claimed design.
